UNITED STATES PATENT OFFICE.

DAYTON BLACKABY, OF LEWISTOWN, ILLINOIS.

PROCESS FOR STITCHING HARNESS.

Application filed April 4, 1923. Serial No. 629,920.

To all whom it may concern:

Be it known that I, DAYTON BLACKABY, a citizen of the United States, residing at Lewistown, in the county of Fulton and State of Illinois, have invented certain new and useful Improvements in Processes for Stitching Harness, of which the following is a specification.

This invention relates to a new process for stitching harness and more especially farm, team and heavy draft traces. The invention essentially consists in concealing and protecting the wax thread from exposure and wear by forming special channels in opposite sides or faces of the harness and stitching the several layers at said channeled points instead of through the edges in the usual manner. It is to be understood that my method of stitching is a special process as distinguished from the "scratched" trace or machine made trace with invisible stitching on one side only.

In the accompanying drawings, in which like parts are designated by like reference characters throughout the several views;—

Figure 1 is a perspective view of a trace stitched in accordance with my new process.

Figure 2 is a transverse section, taken through the trace, showing the special channels on opposite sides or faces preparatory to the stitching operation.

Figure 3 is a similar view, after the stitching operation.

Figure 4 is a view similar to Figure 3, with the channels closed to cover and protect the stitching, and Figure 5 is a vertical transverse longitudinal section, taken on line 5—5 of Figure 3, looking in the direction indicated by the arrow.

Referring to the drawings for a more particular description of my invention, A designates the trace, B the cockeye at one end of the trace, C rivets employed at said end to

add strength and durability to the trace, D the special channels and E the stitching. 45

In accordance with my invention, the opposite sides or faces of the trace are formed, adjacent side edges of the latter, with two or more pairs of longitudinally disposed registering grooves or channels D and the several layers of the trace stitched together by heavy #10 six cord wax thread E. The channels are then closed or sealed as shown in Figure 4 to protect the wax thread from exposure and wear and at the same time 50 add to the appearance of the trace. 55

From the foregoing description taken in connection with the drawing, it is thought that my new process will be fully understood without requiring a more extended 60 explanation.

Having described my invention, what I claim as new and desire to secure by Letters Patent, is:—

The method of stitching harness consisting in juxtaposing a plurality of plies of leather, forming vertically disposed incisions in the outer surfaces of the other plies which are spaced from and disposed parallel with the edges thereof, the incisions 65 in the opposite plies being alined with each other transversely of the plies and having their inner edges spaced from the inner surfaces of their respective plies, spreading the walls of the incisions to form V-shaped 70 channels, passing stitching through the meeting portions of the plies and drawing the stitching into the bottoms of the incisions and channels, and finally closing and sealing the walls of the channels over the 75 stitching to completely enclose the same by pressing the walls of the channels back into substantially their normal positions. 80

In testimony whereof I affix my signature.

DAYTON BLACKABY.
